UNITED STATES PATENT OFFICE.

LOUIS DIESTERWEG, OF ST. LOUIS, MISSOURI, ASSIGNOR, BY DIRECT AND MESNE ASSIGNMENTS, OF ONE-HALF TO GEORGE J. FLIEHMANN AND GEORGE ITTNER, OF SAME PLACE.

DESIGN FOR A BOX-COVER BRACE.

SPECIFICATION forming part of Design No. 29,391, dated September 20, 1898.

Application filed July 13, 1898. Serial No. 685,873. Term of patent 3½ years.

To all whom it may concern:

Be it known that I, LOUIS DIESTERWEG, a citizen of the United States, residing at St. Louis, Missouri, have invented and produced 5 a new and original Design for Box-Cover Braces, of which the following is a specification.

Figure 1 is a perspective. Fig. 2 is a perspective taken from a position substantially 10 at right angles to the first position and looking at the same side.

As shown in the drawings, the leading or 15 essential feature of my design for a box-cover brace consists of the portion 3, the upper edge and one of the side edges of said portion 3 being a curved line 3^a and the other side edge being a straight line 3^b, inclined to an angle of about thirty degrees relative to a vertical line, the portions 4 and 5 extending down- 20 wardly from the portion 3, the inner edges 4^a and 5^a of said portions 4 and 5, respectively, being straight and vertical, the lower edges of said portions being curved lines 4^b and 5^b

and the outer edge 4^c of the portion 4 being a continuation of the curved line 3^a and the 25 outer edge of the portion 5 being a curved line 5^c, connecting the straight line 3^b with the curved line 5^b, and said portions 4 and 5 being separated by the opening or slot 8, the portion 6 projecting laterally from the upper 30 edge of the portion 3 at a point above the upper end of the line 3^b at an angle parallel with the said line 3^b, the free edge of said portion 6 being a curved line 6^a, and the portion 7 projecting laterally from the portion 3 35 on the line 3^b, the free edge of said portion 7 being a curved line 7^a, connecting the curved line 5^c with the curved line 6^a, said portions 6 and 7 being in parallel planes.

I claim—

The design for a box-cover brace substantially as herein shown and described.

LOUIS DIESTERWEG.

In presence of—

SEMER G. WELLS,
CLINTON L. CALDWELL.
